Inventor:

John K. Krieg

United States Patent Office.

JOHN K. KRIEG, OF NEW YORK, N. Y.

Letters Patent No. 70,577, dated November 5, 1867; antedated October 27, 1867.

IMPROVED PEGGING-JACK.

The Schedule referred to in these Letters Patent and making part of the same.

TO ALL WHOM IT MAY CONCERN:

Be it known that I, JOHN K. KRIEG, of the State, city, and county of New York, have invented certain new and useful Improvements in Pegging-Jacks; and I do hereby declare that the following is a full, clear, and exact description of the same, reference being had to the accompanying drawing, which forms part of this specification, in which—

The jack is shown in a side elevation, with a part in section.

My said invention relates to the construction of pegging-jacks which shall be adapted both to boots and shoes without the necessity of any variation, except length of parts to provide for a difference of height.

My invention consists in making the last-holder hollow throughout its entire length, instead of solid, as heretofore made, for the purpose and substantially as herein described, and in the special arrangement and combination, with the said last-holder, of the short lever, to which the gripping power is applied, by which I obtain the greatest amount of gripping power within the required minimum limit of space.

To enable others to make and use my invention, I will proceed to describe the construction and operation thereof.

In constructing my improved pegging-jack, I employ the usual frame, consisting of uprights, A A, erected on and cast with a suitable base, B. I also have a last-holder, C, which has trunnions, C', forming the fulcrum of the clamping movement of the said holder C. D is a pin, projecting from the top of the holder C, on which pin the last is placed, having a socket to receive the pin, all in the usual manner.

My improved jack is intended for boots as well as shoes, and I have therefore shown the standards A A as of sufficient height to give clearance for the leg of the boot; and for the same reason the last-holder C is of equal height with the standards A. The jack is also designed for small as well as large boots and shoes, and hence the size of the pin D is limited by the smaller sizes of lasts. As heretofore made, this pin is cast or driven into the top of the last-holder; but from the necessarily limited size of the pin, as before explained, it is liable to be broken off in the operation of pegging, requiring to be renewed. In the renewal the pin must be drilled out, a tedious and troublesome operation, involving loss of time, and requiring the aid of machinists' tools. Now, one of the objects of my invention is to overcome all these difficulties, and enable the operator, in case of breakage, to renew the pin himself. To do this I have the last-holder C cast hollow its entire length, as shown in the drawing. I then provide a rod, D', of sufficient length to form several pins, and I insert this rod in the hole in the last-holder, leaving the length of one pin projecting above, as represented in the drawing. This I call the pin-rod. In case the pin is broken the operator has only to drive up the rod sufficiently to form another pin, and this may be done without the use of special tools or the aid of a skilled mechanic.

When the last-holder C is long, as for "boot-work," the horizontal lever F, to which the treadle-rod is fastened, is placed some little distance (see drawing) above the fulcrum of the holder C, the practical effect of which is to lengthen the short lever F, thus reducing the liability of breakage by lessening the strain thereon, and yet not have the point of connection therewith of the treadle-rod G removed from over the centre of the jack-frame, for the jack requires to be revolved horizontally during the progress of the work in order to give the operator easy access to all sides of the sole of the boot, and hence this arrangement of the lever F is important, as the end thereof is thus kept immediately over the point of its connection (by the rod G) with the treadle, however the jack may be turned. To facilitate the turning of the jack, I have a collar cast on the bottom of the base B. Said collar is concentric to the treadle-rod G, and sits into an opening in the bench, or in a bed of suitable corresponding shape, fixed in the bench.

The operation of the jack is as follows: The lasted boot or shoe is placed with the sole upward on the jack, the toe resting on a block, H, (said block has small trunnions, f, which take into notches i in the top of the frame,) while the pin D is inserted in the top of the inverted last. Pressure now made on the treadle j draws on the end of lever F, throwing over the top of the holder C and clamping the boot or shoe firmly, holding it in position for the pegging.

I claim as my invention, and desire to secure by Letters Patent—

The construction of the hollow last-holder, in combination with the pin-rod inserted therein, and adjustable for the purposes and as specified.

JOHN K. KRIEG.
